SCREW FEED CENTRIFUGAL PUMP

Augustus C. Durdin, Jr., Niles Center, Ill., assignor
to Chicago Pump Company, Chicago, Ill., a cor-
poration of Illinois

Application August 18, 1934, Serial No. 740,381

7 Claims. (Cl. 103—111)

This invention relates to screw feed centrifugal pumps and its principal object is to provide means for eliminating binding and clogging of the pump. The pump forming the subject matter of this specification is intended primarily for pumping liquids containing solid or semi-solid matter, as for instance sewage, paper pulp and so forth. Ordinarily a screw conveyor and co-operating comminuting means are provided for reducing the solid and semi-solid matter into smaller fragments before they enter the pump impeller, and no claim is made herein to such comminuting means but from experiments made in actual practice, it has been found that the solid and semi-solid matter collected at various parts of the pump and formed obstructions for the screw conveyor and the impeller, the result being that the accumulated solid matter stopped the pump, and it had to be taken apart frequently and cleaned.

In accordance with the present invention, stationary cutting means are provided at the several places where the solid or semi-solid matter is likely to enter clearance spaces between the pump casing and the rotating parts therein, which stationary cutting means co-operate with cutting edges of the rotating parts to sever or cut away from the mass any piece that would otherwise enter the clearance spaces and cause a binding action between the pump casing and the rotating parts therein. By the application of the present improvements to screw feed centrifugal pumps, clogging and binding have been eliminated and the pumps run indefinitely even when subjected to the most rigid tests.

The invention consists in the several novel features hereinafter fully set forth and claimed.

An exemplification of the invention is illustrated in the drawings accompanying this specification in which:

Fig. 1 is a central, vertical longitudinal section through a screw feed centrifugal pump embodying the invention;

Fig. 2 is a vertical cross section taken on the line 2—2 of Fig. 1;

Fig. 3 is a detail, fragmental cross section taken on the line 3—3 of Fig. 1;

Fig. 4 is a detail, fragmental horizontal section taken on the line 4—4 of Fig. 3;

Fig. 5 is a detail, fragmental, vertical section taken on the line 5—5 of Fig. 3;

Fig. 6 is a vertical cross section taken on the line 6—6 of Fig. 1;

Fig. 7 is a vertical cross section taken on the line 7—7 of Fig. 1, and

Fig. 8 is a detail cross section taken on the line 8—8 of Fig. 7.

Referring to said drawings, the reference character 10 designates a base upon which are mounted two end brackets 11, 12, containing bearing boxes 13 in which is journaled the pump shaft 14. Between the end brackets is the pump casing 15, which is composed of a cylindrical part 16 and a volute part 17 communicating therewith through an opening in the discharge end of the cylindrical part. A suction inlet 18 enters through the side of the cylindrical part of the pump casing and a discharge outlet 19 leads from the volute part thereof. Desirably the end brackets are formed with upright circular parts 20, 21, that comprise heads for the pump casing and are bolted thereto, and the cylindrical part of the casing is formed with a circular flange 22 which is bolted to the volute part and forms one head thereof. The exact form of casing construction is, however, not material to the invention, broadly considered. On the heads 20, 21 are stuffing boxes and the usual water seals 23 for preventing leakage around the pump shaft. The end brackets 11, 12 and pump casing 15, composed of the cylindrical part 16 and volute part 17, being made of separate parts bolted together, the pump casing may be adjusted circumferentially around the axis thereof to locate the suction inlet or the discharge outlet or both, in vertical or inclined positions instead of the horizontal position illustrated. This arrangement is of a special importance in connecting the pump to the pipe lines since either the incoming or outgoing line or both lines to and from the pump may be horizontal, vertical or inclined. The entire casing 15, or either the cylindrical part 16 thereof or the volute part 17, may be rotated relative to the end brackets to locate the discharge outlet at various desired positions around the axis of the casing.

Mounted on the pump shaft are a screw conveyor 24 and an impeller 25 formed separately or integrally as desired, the screw conveyor rotating in the cylindrical part of the pump casing and the impeller rotating in the volute part. The screw conveyor has one or more helical blades 26 which join with the impeller blades 27 of the impeller and serve to convey solid and semi-solid matter to the impeller. Cooperating with the blades of the screw conveyor are comminuting means for cutting, breaking, tearing, shearing or otherwise comminuting solid and semi-solid matter that enters the pump, here shown in the form of bars 28, that extend longitudinally along the internal face of the cylindrical part of the cas-

ing and are seated in grooves formed in the internal face and secured therein by bolts 29. The comminuting bars project beyond the cylindrical face of the casing and co-operate with the screw conveyor blades to comminute the solid and semi-solid material besides assisting in feeding the matter forward toward the impeller.

In the operation of the pump thus far described the impeller produces the suction necessary to move the liquids and solid and semi-solids into the pump casing, the screw conveyor comminutes the solids and semi-solids and feeds the comminuted mass to the impeller and the latter discharges the liquids and comminuted mass from the pump. No claim is made to the pump construction thus far described, and I shall now proceed to describe the novel features which comprise the present invention.

One of the places where the solids or semi-solids cause a binding effect is at the clearance space between the helical blades 26 of the screw conveyor and the head 20 of the cylindrical part of the casing. Stringy material ordinarily becomes caught on the ends of the blades and to prevent the accumulation of such matter with the attendant binding at this place, cutting bars 30 are let into grooves in the head 20 and secured therein by bolts 31. A slight clearance is left between the terminal ends of the screw conveyor blades 26 and the head 20, and the cutting bars 30 project from the internal face of the head into this clearance space and co-operate with the end edges of the blades 26 to cut or shear off any stringy material or other pieces of material that lap over the end edges of the blades. The material being severed at the overlapping part, it is readily fed forward by the screw conveyor and the binding action is entirely eliminated at this place.

Another place where the material is likely to wrap around the blades is at the place where the blades of the screw conveyor merge into or meet the impeller blades. It was found that when the comminuting bars 28 formerly extended to the discharge end of the cylindrical wall of the casing, a mass of stringy material would wrap around the blades at this point and would be carried around until the mass struck against the side of a comminuting bar at its terminal end, thereby stopping the pump. To eliminate this occurrence the comminuting bars 28 terminate short of the discharge end of the cylindrical part of the casing (see Fig. 5) and a cutting ring 32 is let into the cylinder, which ring fits tightly therein and co-operates with the helical blades of the screw conveyor to cut or shear off any material that may lap over said blades at the place where the blades travel along the edge of the ring. It is to be observed that a considerable portion of the mass is carried along the internal cylindrical face of the casing by the helical blades and some moves along the side of the comminuting bars 28. As the mass reaches the cutting ring 32 any material that overlaps the helical blades is cut or sheared off at the ring, passing on to the impeller without being caught around its edge, and as a consequence binding or clogging at this point has been eliminated.

Another place where binding is likely to occur is at the clearance space between the impeller blades 27 and the head 22 of the volute 41. Stringy material and other material is likely to find its way into this clearance space and cause sufficient binding to stop the pump. To prevent

material from entering this clearance space, I provide cutting bars 33 (see Figs. 3 to 5) that are let into grooves in the internal face of the head 22 and are secured therein by bolts 34. The cutting bars 33 project into the clearance space between the head and side edges of the impeller blades and co-operate with the blades to cut or shear off material that overlaps the blades, thereby enabling the blades to discharge the severed pieces along with the flowing liquids. Desirably the face of the head 22 is relieved along the cutting side of the bars 33 as at 35 to facilitate the cutting action and to provide space for the cut away pieces. The cutting bars 33 project in front of the cutting ring 32.

In the form of impeller shown the blades project from a disc like wall 36, located adjacent the head 21 and narrow impeller blades 37 similar to the blades 27 are provided on the side of the wall 36 opposite the blades 21. To prevent binding in the clearance space between the blades 37 and the head 21, cutting bars 38 (see Fig. 7) similar to the cutting bars 33 are provided on the head 21. If desired the faces of the head 21 and the head 20 may be relieved adjacent the cutting bars in the same manner as the face of the head 22 is relieved at the cutting bars 33 (see Fig. 4).

It has been found that with the ordinary throat leading from the volute to the discharge inlet, the comminuted matter would clog the throat of small pumps. To overcome this, instead of forming a throat of circular cross section, as usual, in small pumps I have widened the throat considerably as at 40 (see Figs. 7 and 8) making a vertically elongated opening or passage from 35 which leads an outwardly flaring throat, and find that this change does not impair the efficiency of the pump in any manner, but does effectively prevent clogging in the throat.

By providing cutting means at the several places where solid or semi-solid material is likely to cause binding between the casing and rotating parts, I have provided a pump for handling liquids containing solid or semi-solid matter wherein the possibility of binding or clogging is entirely eliminated. More specifically by providing cutting means on all sides of the screw propeller and impeller blades that rotate in close proximity to stationary walls, I eliminate the possibility of clogging due to the accumulation of solids between the closely spaced relatively rotatable parts. The pump is particularly adapted for pumping sewage, although its use is not limited thereto as it is highly efficient for pumping liquids containing other solids or semi-solids.

While the invention has been shown and described in connection with a screw feed pump, it is not the intention to limit it thereto, as it is applicable to many types of centrifugal pumps. It is also to be observed that both the screw propeller and the impeller propel comminuted solids. It is to be understood therefore that the term "propelling element" as used in the following claims includes either a screw conveyor or an impeller or both.

More or less variation of the exact details of construction is possible without departing from the spirit of this invention; I desire, therefore not to limit myself to the exact form of the construction shown and described, but intend, in the following claims to point out all of the invention disclosed herein.

I claim as new and desire to secure by Letters Patent:

1. A pump for pumping liquids containing solids or semi-solids, comprising a casing having a cylindrical part and a volute part opening thereto, some of the faces of the cylindrical and volute parts being flat, a screw conveyor rotating in the cylindrical part and an impeller rotating in the volute part, there being an inlet in the cylindrical part of the casing adjacent the flat wall thereof, said screw conveyor and impeller having edges traveling throughout their entire extent in close proximity to the flat faces of the casing, and means for maintaining free clearance spaces between said flat faces of the casing and edges of the screw conveyor and impeller comprising cutting elements on the casing entering said clearance spaces and co-operating with said entire edge portions of the screw conveyor and impeller to shear off material that is carried to said clearance spaces.
2. A pump for pumping liquids containing solids or semi-solids, comprising a casing having a cylindrical part and a volute part opening thereto, some of the faces of the cylindrical and volute parts being flat, and there being an inlet in the cylindrical part, a screw conveyor rotating in the cylindrical part of the casing, and an impeller rotating in the volute part, said screw conveyor and impeller having edges traveling throughout their entire extent in close proximity to the flat faces of the casing, and means for maintaining free clearance spaces between said flat faces of the casing and edges of the screw conveyor and impeller comprising cutting bars seated in grooves in said flat faces at the inlet ends of the screw and impeller, and projecting into said clearance spaces and co-operating with said edge portions of the screw conveyor and impeller to shear off material that is carried to said clearance spaces.
3. A pump for pumping liquids containing solids or semi-solids, comprising a casing having a cylindrical part and a volute part opening thereto, some of the faces of the cylindrical and volute parts being flat, and there being an inlet in the cylindrical part, a screw conveyor rotating in the cylindrical part of the casing, and an impeller rotating in the volute part, said screw conveyor and impeller having edges traveling throughout their entire extent in close proximity to the flat faces of the casing, and means for maintaining free clearance spaces between said flat faces of the casing and edges of the screw conveyor and impeller comprising cutting bars seated in grooves in said faces at the inlet end of the screw and impeller and projecting into said clearance spaces and co-operating with said edge portions of the screw conveyor and impeller to shear off material that is carried to said clearance spaces, the faces of the casing being relieved in front of the cutting edges of the cutting bars.
4. A pump for pumping liquids containing solids or semi-solids, comprising a cylindrical

casing having a head and a suction inlet adjacent thereto, a screw conveyor rotating in said casing with the end edge of its conveyor blade traveling in close proximity to said head, and a cutting bar on said head projecting into the clearance space 5 between the head and the end of the conveyor blade and co-operating with said end of the blade to shear off material that is carried to said clearance space.

5. A pump for pumping liquids containing 10 solids or semi-solids, comprising a casing having a cylindrical part and a volute part opening thereto, the casing having a flat face joining the cylindrical part with the volute part, a screw conveyor rotating in the cylindrical part of the 15 casing and an impeller rotating in the volute part, and a cutting ring extending circumferentially about the screw conveyor and secured in the cylindrical part of the casing adjacent the flat wall of the volute part and co-operating with 20 the peripheral edge of the screw conveyor to shear off material carried to the cutting ring.

6. A pump for pumping liquids containing 25 solids or semi-solids, comprising a casing having a cylindrical part and a volute part opening 25 thereto, some of the faces of which are flat, a screw conveyor rotating in the cylindrical part of the casing and an impeller rotating in the volute part, a comminuting bar extending longitudinally in the cylindrical part of the casing 30 and a cutting ring extending circumferentially about the screw conveyor and secured in said cylindrical part of the casing adjacent a flat face between the cylindrical and volute parts, said cutting ring co-operating with the screw conveyor 35 to shear off material that is carried to the cutting ring.

7. A pump for pumping liquids containing 40 solids or semi-solids, comprising in combination, a pump casing composed of a cylindrical part and 40 a volute part, one end of the cylindrical part being closed and the other end being open and opening to the volute part, and there being a suction inlet on the cylindrical part intermediate its ends and a discharge outlet in the volute part, 45 a screw conveyor rotating in the cylindrical part and an impeller rotating in the volute part, the screw conveyor having blades traveling in close proximity to the end and side wall of the cylindrical part of the casing, and the impeller having 50 blades traveling in close proximity to the side walls of the volute part of the casing, and cutting bars on all of said casing walls, outlining the screw conveyor and impeller except around the periphery 55 of the impeller, said cutting bars entering the clearance spaces between the blades and casing walls, and co-operating with said blades to prevent solid or semi-solid matter from collecting and binding between any of the casing walls and 60 the blades.

AUGUSTUS C. DURDIN, JR.
